UNITED STATES PATENT OFFICE

TALIAFERRO JAMES FAIRLEY, OF STERLINGTON, LOUISIANA, ASSIGNEE, BY DIRECT AND MESNE ASSIGNMENTS, OF ONE-HALF TO W. J. HUNTER AND ONE-HALF TO MARY P. HUNTER, BOTH OF SHREVEPORT, LOUISIANA

PROCESS OF TREATING OILS

No Drawing.

Application filed May 21, 1928. Serial No. 279,605.

The present invention relates to the treatment by distillation of a variety of oils which may be particularly described as oils of the animal and vegetable series, essential oils, the members of all of which series are well known, and to a series of hydrocarbons known as the terpenes, the latter class being generally recognized as containing a compound having the empirical formula $C_{10}H_{16}$.

10 In this latter series are contained various wood oils, pine oils, oils which are the product of wood distillation, oils obtained from various pine oils, resin oils, tar oils, oils from resinous wood, sawdust, and also oils which are produced by the treatment of tree and vegetable gums.

The object of the invention is to distill any one of the oils of the several series mentioned in such a manner as to obtain a distillate and a residual product, both of which are found to have marked advantages, due to their physical and chemical constitution.

20 For example, the distillate obtained has been found to have a marked importance as a solvent particularly in connection with the reclaiming of vulcanized rubber.

The oil residue which remains, and which may be further treated by various refining methods, if necessary, has been found to possess characteristics definitely indicating its usefulness as a lubricating oil equal to the best grades of the mineral product.

One of the most important features of the process resides in the use of an agent, for example a clay and particularly a colloidal clay having all or some of the properties of bentonite, which apparently does not enter into the reaction, but the presence of which changes the physical and chemical constitution of the material being distilled, so that the distillate recovered as well as the residual oil, has marked characteristics which distinguish it from the original charge.

While my invention, as stated, is applicable to animal and vegetable oils, essential oils and various other oils, I have found it particularly useful and advantageous in connection with oils of the terpene series and their homologues.

50 There is, of course, a large number of

oils comprised in this series, both natural and synthetic, and I will mention a few such as the monocyclic, bicyclic, tricyclic, sesquicyclic, polycyclic and hydrocyclic. The members of these groups can be readily determined from any chemistry.

55 In order to illustrate the invention, I shall describe the process as used in connection with turpentine, probably the most representative and important of the terpenes, and it will be understood that the turpentine may be that produced in wood distillation as well as the usual and well known gum spirits of turpentine. It will be understood that in mentioning these two, they are simply for purposes of illustration and I do not confine myself by any means to these specific terpenes.

60 In carrying out the invention the turpentine from either of the above sources is run into a suitable still in which there has been charged a sufficient quantity of clay which is arranged in a position where it may suitably come in contact with the turpentine. The quantity of clay, of course, will depend upon the bulk of turpentine to be treated and may be described for some cases as ten per cent by weight of the turpentine. This is only approximate and may be varied at will, depending upon the nature of the product, the apparatus and the end products which it is desired to obtain.

65 With the turpentine and clay in the still, the mass is gently or slowly heated for a short period or until it has the appearance of boiling.

70 After the mass has reached a temperature which produces a slow boiling, the temperature is maintained for a short period to continue the mass in this condition.

75 During this preliminary or initial heating a small amount of distillate will, of course, pass off as vapor which will be condensed and collected and the small amount of water separated. In some cases, it is advantageous 80 to maintain the vapors produced by these steps in the still pending further operation of the process.

85 It will be understood that in some cases this preliminary treatment or treatments will not 90

55

100

be necessary or the maintaining of the boiling condition eliminated, but I find these steps valuable for causing a complete contact of the clay and oil.

- 5 The period of heating, of course, cannot be definitely stated since it will necessarily vary in accordance with conditions surrounding the operation, such as the apparatus and character of oil and clay, and these likewise 70 affect the temperature to which the mass need be heated to promote boiling and to maintain such condition.

10 Of course, during the heating period, the clay coming in contact with the material will cause chemical reaction and rearrangement 75 and physical changes, resulting in the formation of new compounds and also this reformation will continue to some extent during the subsequent distillation. The amount and 80 speed with which the chemical and physical changes take place will, of course, vary with the conditions surrounding the heating and distilling operation, so that in some cases rapid reaction will take place, while in other 85 cases, the reaction will be slow and may not occur completely until the subsequent fractionation is in progress.

15 It is enough to say, however, that by reason 90 of the process which I employ, the character of the oil under treatment, in this particular case turpentine, undergoes a physical and chemical change, resulting in the fractional cuts obtained. This may be due in some cases 95 to a cracking effect upon the oil induced by the distillation in the presence of the clay.

20 When a sufficient time has elapsed and it would appear that the contact between the oil and clay has been adequate, the temperature of the still is raised gradually to distil or 100 fractionate the various volatile constituents of the oil.

25 This fractionating generally continues to a point in the neighborhood of 250° C., where I have found with usual runs of turpentine 105 that the lighter fractions cease to come over and a heavier fraction begins to come off. I may stop at this point unless it is desired to have a distillate containing a portion or all of the heavier fractions. Where I have continued distillation beyond 250° C. the distillate shows a greenish tint and fluorescence 110 and has the characteristics of a light lubricant indicating the presence of oily fractions. Such distillate may in some cases be used as 115 a lubricant, rust remover, a gun oil and for other purposes, as furniture polish and floor oils. The oil content will, of course, increase in the distillate as the fractionating temperature rises above substantially 250° C. I have 120 found that a distillate containing a greater or less quantity of the heavy fractions may be used as a lubricant for purposes dependent upon the weight of oil required.

30 In the fractionating of the turpentine in 125 the presence of the clay, I observe that the

fractions at various stages possess lighter specific gravities, for example some of the fractions at the increased temperature range have a lighter specific gravity than those of a lower boiling range. For example, the distillate collected up to 180° C. has a specific 70 gravity of 0.853-0.855, that from 180° to 190° C. a specific gravity of 0.844 and that from 190° C. to 250° C. a specific gravity of 0.862. The figures given are at 15.5° C. and 75 of course result with the use of clay as described.

It suffices, however, to say that in most cases the fractions which are taken off up to 80 substantially 250° C. are of relatively lighter specific gravity than the material treated, while above this point the fractions usually have a viscous character.

I stop primarily at the point where the 85 heavy viscous fractions would begin to come over because the distillate produced up to this point is valuable as a solvent and this quality is sometimes changed after an appreciable portion of the heavier fractions are 90 mixed with such distillate. Such a distillate having an oily content to various degrees, however, may be used as a lubricant if desired.

Moreover, by discontinuing the distillation 95 at the point mentioned, I find that the residue is a viscous, oily mass, which I propose to employ as a lubricant.

It will be understood that the distillate which is taken off up to 250° C., may be subsequently refined by redistillation, and by 100 that I mean with or without the presence of clay, in accordance with the nature of the distillate and the product it is desired to finally obtain.

105 In the same manner, the distillate may be fractionated off to obtain various compounds.

The viscous, oily residue may be drawn off and redistilled, or fractionated with or without the presence of clay, or it may be permitted to remain in the still and the distillation continued and the heavy fractions separately collected. In either case, of course, it will be possible to collect various fractions and to produce an oil which may meet a great 110 variety of tests for any particular use.

115 The effect of the clay may be described as catalytic, since I do not find that it is chemically changed or combines with the products to any appreciable degree, although in some cases, there may possibly be a chemical reaction between the material treated and the components of the clay.

120 The clay may also exert various absorbent and adsorbent tendencies upon constituents of the material being treated, as well as upon any moisture present, these being properties of the colloidal clays such as the bentonites.

125 The distillate obtained up to 250° C., I have found to possess a lower specific gravity than the turpentine originally charged and

in the particular case, here illustrated, a specific gravity below substantially 0.858, namely 0.853, and, in many cases, the specific gravity will be considerably lower, depending upon the amount of fractionating and the nature of the material treated.

The amount of distillate obtained, of course, will vary, but it will in most cases constitute substantially 50 to 75 per cent of the original bulk of material being treated.

The distillate is found to possess chemical and physical characteristics different in varying degrees from the original material and this I attribute to the process of distillation described and, of course, will also vary with the nature of the clay employed.

The distillate forms a desirable solvent and one purpose for which it is especially useful is in the devulcanization and reclaiming of vulcanized rubber, as well as a solvent for various resins and gums. Where the distillate contains heavier oil fractions it may, as stated, be used as a lubricant.

The oil which I have described above and referred to as a residue after the fractions up to 250° C., have been removed, will be useful as a lubricant and obviously for any other purposes to which oils of the same character are applied.

This oil is clear yellowish, has a bright fluorescence, agreeable odor and is quite viscous. The viscosity of the oil recovered has been found upon test, to be in the neighborhood of 130 Saybolt, with a flash point of about 240° F. (Cleveland open cup) and a content of residual carbon of substantially 0.05 per cent. In some cases, this oil need not be redistilled or refined, but for lubricating purposes, as for instance, an automobile lubricant, it is desirable to raise the flash point and viscosity, which I have done, by fractionating off possibly ten per cent of the lighter fractions, giving a flash point well over 300° F. and a proportionately increased viscosity.

The lubricating oil produced has a very pleasing fluorescence, particularly possessing both before and on redistillation a greenish tint, which is comparable with the best known mineral lubricating products.

Aside from use as a lubricant for automobiles, the oil is an excellent cylinder lubricant and can be equally well used for sewing machine oil. In fact, I have found it possible to employ the oil either before it is refined or after it is refined in an innumerable number of applications, where the mineral product or oils from other sources are used.

The specific gravity of the residual oil before it is refined varies with the material under treatment, the clay employed, the nature of the apparatus and the time and temperature elements, but in the case of a turpentine treatment, it was substantially 0.9 to 1.00 more or less, so that it is comparable with

the petroleum oils obtained from most oil fields in this country, as well as abroad. It can be, as stated, subsequently refined to raise or lower the flash point, burning point, viscosity and in general may be treated to conform to a product equal if not more efficient than that obtained from mineral oils.

I have already stated that the fractionating may continue to any desired extent, in accordance with the character of distillate it is desired to obtain i. e. a solvent or lubricant, and have indicated as the usual point where the cut between the solvent fractions and the lubricating fractions will be made as being about 250° C.

I have also stated that the distillate may be again refined or distilled fractionally, if desired and that such distillation in either case may take place in the presence of the clay, although this is not necessary.

I have also stated that the oily residue or the lubricating cut may be run off from the still and further refined by distillation or fractional distillation in the presence of the clay, as well as without the use of this agent, and also that distillation of the lubricating residue may continue in the still.

In referring to a specific treatment with one of the terpenes, namely turpentine from wood distillation or from gums, I do not mean to be limited to this specific product because, as stated, the invention is equally useful in connection with a great variety of the terpenes, as well as vegetable, animal and essential oils and their homologues, many of which contain terpene compounds and which will all be treated in substantially the same manner. It is possible naturally, that some modifications may be necessary by reason of the nature of the product being treated, as, for instance, its boiling range or where it is impure or is combined with other materials, but in general the process herein described will be followed.

In addition to bentonite or a clay or colloidal clay having the effect of bentonite the following may be used: Death Valley clay, wilkinite, montmorillonite, fuller's earth, diatomaceous earth, infusorial earth, bauxite, kieselguhr, silica gel, pyrophyllite, leverrierite, pipe clay.

I have been particularly successful in the use of bentonite or colloidal clays related to bentonite or of the same series of which there are many members having various analyses but all generally similar and depending upon their source and occurrence.

Bentonite is the name given to a group or series of clay-like materials having a content of SiO_2 about 58%, and a content of about 22% of Al_2O_3 , with small contents of Fe_2O_3 , CaO , MgO , K_2O and others. Several of the clays above mentioned possess the same adsorbent and absorbent tendencies of bentonite as well as a very similar analysis, while others

may be treated in various ways to acquire similar characteristics. In referring to bentonite in the claims, it is to be construed as covering true bentonites as well as clays of similar 5 chemical analysis either raw or prepared, and possessing similar colloidal properties.

In employing any one of the clays or agents above listed, it will be understood that the 10 chemical and physical changes or cracking which occur, may take place during the preliminary heating before actual fractionating or distilling commences, or during the fractionating, and in fact entirely in either period or in both periods. Naturally, the 15 action will depend upon the materials treated, the agent employed, and the time and temperature elements.

The residual oil which I have referred to as the lubricating cut will constitute anywhere 20 from five to fifty per cent of the total bulk of material treated and, of course, is dependent upon the circumstances surrounding the 25 operation.

It is generally understood that the standard specific gravity for turpentine varies 25 from 0.860 to 0.872 at 15.5° C. However, in some cases, a satisfactory turpentine may have as low a specific gravity as 0.858, and a maximum of 0.875. Such products may be 30 treated with equal efficiency.

It will be observed that the distillate which I recover as the solvent cut, has a lower specific gravity than either of the turpentines employed and the lubricating cut possesses a 35 specific gravity which in general is greater. In some cases, however, this lubricating cut will be below .9 and as such, will be a satisfactory lubricant without further treatment.

40 Furthermore, it will be understood that the quantity of clay may be increased or decreased with various results, depending upon the nature of the materials and other circumstances surrounding the operation and I 45 have also discovered that in many cases, the clay can be reused and that the operation can continue by adding a small quantity of fresh or green clay to that already in the still, without necessitating a fresh supply of clay 50 for each operation.

In the treatment of the crude distillate from ordinary wood distillation, whether by the destructive process or the steam process, there occurs a fraction which is generally 55 known as an intermediate fraction. The amount of this fraction varies in each operation, but I have found that this intermediate fraction, which is a terpene, can be recovered and treated with equal facility by the process 60 here described.

In the preliminary heating to obtain the boiling of the bulk of material, the time element cannot be definitely stated because I have found it to vary with different types of 65 stills, as well as with different classes of ma-

terials and agents. In some cases, an hour will suffice for the preliminary heating and an equal period for the maintaining of the constant temperature or boiling, but, in other cases, the periods may be longer and may 70 vary.

As stated the material treated which is turpentine in the present case, by reason of the process described is caused to produce a fractional distillate of less specific gravity than 75 the turpentine as well as a residual cut or oil residue of greater specific gravity. This is accomplished, of course, with the aid of the clay, but it will be noted that no recourse is had to pressure and that the temperatures 80 employed are well within the range of cheap and efficient operation. In some cases depending upon the circumstances or the nature 85 of the clay and material as well as the apparatus available, some pressure may be required, but for many operations it is not necessary.

While I have referred to and illustrated a specific treatment with turpentine, which is a prominent representative terpene, it will be 90 clear that other of the terpenes such as lemonene, terpinolene, phellandrene, sylvestrene, eriganene, crithmene, moslene, synthetic menthadienes, terpinene, a-pinene and b-pinene, camphene, bornylene, sabinene, thymene, fenchene, a-pinolene, b-pinolene, da-crydene, trycylene, rosin oils, resin oils, pine oils, tar oils, rosin spirits, "light" oil, terpin, terpin hydrate, linalool, caophyllene, humulene colophene and many others as well as oxidized compounds, such as absinthol, borneol, cajeputol, carveol, carvone, camphors, cineol, citronellol, coriandrol, eucalyptol, fenchone, gernaiol and citral and many others may be 95 used.

Terpenes from the various wood oils, pine oils, oils produced from wood distillation, oils from various pine oils, rosin oils, tar oils, oils from resinous wood, sawdust, oils from the treatment of tree and vegetable gums are 100 those with which I have had the most success.

The essential oils, some of which include terpenes, in addition to those mentioned above are, benzine derivatives, resins i. e. oleo resins, thymol, menthol, oil of almonds, oil of bergamot, oil of cajeput, cedar oil, chamomile, cinnamon oil, oil of cloves, eucalyptus oil, geranium oil, lavender oil, oil of lemon, oil of peppermint, mustard oil, attar of roses, oil of sassafras, oil of wintergreen, oil of rue 110 and oil of wormwood.

Some of the vegetable oils also contain terpenes and in addition to those heretofore mentioned, I may treat cotton seed oil, linseed oil, sesame, olive oil, soya bean oil, hemp oil, tung oil, sunflower oil, poppy oil, corn oil, and castor oil, as well as palm oil and coconut oil.

Various animal oils including fish oils such as menhaden oil, liver oils, such as cod liver 130

oils and blubber oils such as whale oils and blackfish oils, may likewise be treated.

It is obvious that various fractions may be collected separately and this applies both to the lighter fractions and the heavier ones. Specific fractions have been and may be found useful for many purposes. I have stated that for light lubricating oils, for instance, it may be desirable to run above 250° C., and in the same manner a lubricating cut or residue obtained by running at a lower range will provide a lubricating oil of greater viscosity useful for many applications.

Moreover, I have found that after distilling the lighter fractions and the heavier ones, a suitable pitch will be produced which is superior to the pitch obtained from usual sources.

It will also be understood that the distillate to which I have referred is volatile and possesses a pleasing odor which is different from that of turpentine.

It will be understood that various of the lighter fractions may be collected and used separately. For instance, the fractions from 150° to 170° C., will provide a satisfactory solvent, those from 170° to 190° C. an equally satisfactory solvent and those from 190° to 250° C., which are a very small part, a fraction which is not quite so satisfactory. I combine any one or more of these fractions to form a suitable solvent or I may use each of them separately or combine all of them in a single distillate or volatile oil.

In addition to the fractions mentioned, I also use the fractions up to 150° with equal success, either combining them with the other fractions, or using the fractions individually.

What I claim is:

1. The process of treating wood distillate fractions of the terpene series derived from the direct distillation of wood which comprises subjecting at least one terpene wood distillate fraction to distillation in the presence of a clay having the action of a catalyst, and collecting the resultant vapors.

2. The process of treating wood distillate fractions of the terpene series derived from the direct distillation of wood which comprises treating at least one terpene wood distillate fraction by distilling off a portion thereof in the presence of a clay having the action of a catalyst, collecting resultant vapors, and recovering residual oil.

3. The process which comprises subjecting one of the oils of the terpene series derived from the distillation of wood to gentle heating in the presence of a clay having the action of a catalyst until the mass begins to boil, and thereafter fractionally distilling the mass in the presence of the clay, and collecting the resultant vapors.

4. The process which comprises subjecting one of the oils of the terpene series derived from the distillation of wood to a gentle heat-

ing in the presence of a clay having a catalytic action until the mass begins to boil, and thereafter distilling off a portion of the mass, collecting the resultant vapors, and recovering a residual oil.

5. The process which comprises subjecting turpentine to distillation in the presence of a clay having a catalytic action and collecting the vapors.

6. The process which comprises subjecting turpentine to distillation in the presence of a clay of the bentonite type and collecting the vapors.

7. The process which comprises subjecting turpentine to distillation in the presence of a clay having a catalytic action and collecting at least one of the fractions obtained within a boiling range up to substantially 250° C.

8. The process which comprises treating turpentine by distilling off a portion thereof in the presence of a clay having a catalytic action, collecting the fractions, and recovering as a residue an oil boiling above substantially 250° C.

9. The process of treating turpentine to recover a distillate therefrom and a residual oil which comprises distilling the turpentine in the presence of a clay of the bentonite type, collecting the fractions boiling up to substantially 250° C., and recovering as a residue an oil boiling above substantially 250° C.

10. The process of treating turpentine to recover a distillate therefrom and a residual oil which comprises distilling the turpentine in the presence of a clay of the bentonite type, collecting the fractions within the boiling range up to substantially 250° C. to obtain a distillate of lower specific gravity than the turpentine, and recovering as a residue an oil having a higher specific gravity than the turpentine.

11. The process of treating turpentine to recover a distillate therefrom which comprises distilling the turpentine in the presence of a clay of the bentonite type, collecting a distillate having a specific gravity below that of the turpentine, and discontinuing distillation to obtain as a residue an oil having a specific gravity above that of the turpentine.

12. The process which comprises subjecting turpentine in the presence of a clay of the bentonite type to a gentle heating below the boiling point of the turpentine, distilling the turpentine in the presence of the clay, and collecting fractions boiling up to substantially 250° C.

13. The process of treating turpentine which comprises subjecting the turpentine to a gentle heating below its boiling temperature in the presence of a clay of the bentonite type, distilling a portion of mass in the presence of the clay, and recovering as a residue

an oil having a boiling point above substantially 250° C.

14. The process which comprises subjecting turpentine to distillation in the presence of a clay having a catalytic action, collecting the fractions boiling up to substantially 190° C., and recovering as a residue an oil of higher specific gravity than the turpentine.

5 In testimony whereof I have hereunto set
10 my hand.
